COMBINED LAMP BASE AND ABACUS

James A. McFadden, Princeton, N.J.

Application September 15, 1958, Serial No. 52,652

Term of patent 7 years

(Cl. D48—20)

Fig. 1.

Fig. 2.

Figure 1 is a perspective view of a combined lamp base and abacus showing my new design; and

Figure 2 is a perspective view thereof as seen from the right of Fig. 1.

The side of the article not shown is substantially the same in appearance as the side shown.

The light bulb shown in broken lines is for illustrative purposes only.

I claim:

The ornamental design for a combined lamp base and abacus, substantially as shown and described.
